US0D1001017S

(12) **United States Design Patent** (10) **Patent No.:** **US D1,001,017 S**
(45) **Date of Patent:** **** Oct. 10, 2023**

(54) **COMPACTABLE VEHICLE AND/OR
REPLICA**

(71) Applicant: **Honda Motor Co., Ltd.**, Tokyo (JP)

(72) Inventor: **Michael Jin Kim**, Long Beach, CA
(US)

(73) Assignee: **HONDA MOTOR CO., LTD.**, Tokyo
(JP)

(**) Term: **15 Years**

(21) Appl. No.: **29/823,691**

(22) Filed: **Jan. 19, 2022**

Related U.S. Application Data

(62) Division of application No. 29/719,457, filed on Jan. 3, 2020, now abandoned.

(57) **CLAIM**

The ornamental design for a compactable vehicle and/or replica, as shown and described.

DESCRIPTION

FIG. 1 is a front and left side perspective view of a compactable vehicle and/or replica embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the figures are included for the purpose of illustrating portions of the compactable vehicle and/or replica and form no part of the claimed design.

1 Claim, 7 Drawing Sheets
